Primary Examiner—A. Hugo Word*Assistant Examiner*—Lavone Tabor*Attorney, Agent, or Firm*—Donald S. Cohen[57] **CLAIM**

The ornamental design for an interdental toothcleaner holder for vibrating handle, as shown and described.

DESCRIPTION

FIG. 1 is a perspective view of the interdental toothcleaner holder;

FIG. 2 is a top end and view of the interdental toothcleaner holder;

FIG. 3 is a view of one side of the interdental toothcleaner holder;

FIG. 4 is a bottom view of the interdental toothcleaner holder;

FIG. 5 is a view of the other side of the interdental toothcleaner holder;

FIG. 6 is a top plan view of the interdental toothcleaner holder; and,

FIG. 7 is a bottom end view of the interdental toothcleaner holder.

The broken lines are for illustrative purposes only and form no part of the claimed design.
